INVENTOR

UNITED STATES PATENT OFFICE.

JAMES MASKER, OF HAMMOND, INDIANA.

CAR-ROOF.

No. 913,412.

Specification of Letters Patent.

Patented Feb. 23, 1909.

Application filed April 13, 1907, Serial No. 367,946. Renewed December 29, 1908. Serial No. 469,774.

To all whom it may concern:
Be it known that I, JAMES MASKER, a citizen of the United States, residing at Hammond, in the county of Lake and State of Indiana, have invented a certain new and useful Improvement in Car-Roofs, of which the following is a full, clear, and exact description, reference being had to the accompanying drawings; forming a part of this specification, and to the model filed herewith.

My invention relates to new and useful improvements in car roofs of that class commonly known as "inside roofs" and particularly contemplates the provision of an inside roof constructed for the greater part of metal plates so held by the ridge pole and carlines that they are capable of independent movement to overcome the heavy strain put upon them, while at the same time forming an absolutely water-tight construction.

My invention further and specifically resides in the following features of construction and arrangement as will be hereinafter described with reference to the accompanying drawings, forming a part of this specification, in which like characters are used to designate like parts throughout the several figures, and in which,

Figure 1 is a perspective view of a portion of a roof constructed in accordance with my invention, Fig. 2 is a similar view of one of the metal plates used therein, Figs. 3 and 3^a are respectively a front elevation and a sectional view of one of the securing elements, Figs. 4 and 5 are similar perspective views of intermediate and end carlines respectively, Fig. 6 is a perspective view of the ridge pole, Fig. 7 is a transverse sectional view through a portion of a completed car roof constructed in accordance with my invention, and Fig. 8 is a perspective view of one of the carline end caps.

In the practical embodiment of my invention and with particular reference to the drawings, I provide a ridge pole A¹ having longitudinal undercut channels A² and openings A³ therethrough communicating with said channels. C⁶ indicate a number of rectangular metal plates having three of their sides formed with upstanding flanges C⁶ having their longitudinal edges curled about metal rods C⁷ to strengthen the same, and having their abutting short edges soldered together. The intermediate and end carlines B² and B³ and B⁴ respectively are each

formed with reduced ends B⁷ adapted to fit snugly within the openings A³ in the ridge pole A¹. The intermediate carlines B² are further formed on the lower face with parallel channels B⁶ while the end carlines B³ and B⁴ are provided on their lower face with a single channel B⁶, said channels B⁶ and B⁷ being designed to receive loosely therein the longitudinal flanges C⁶ of the metal plates C⁸ arranged between the carlines, the end flange C⁶ of said plates being provided with an angular extension flange 9 having an upwardly curled outer edge bent about a metallic rod C⁷ and adapted to be carried within the channels A² of the ridge pole A¹, to form a closure for the upper ends of the carlines B² thus forming with said plates, said carlines and said ridge pole a perfectly water-tight structure while permitting the metal plates C⁸ sufficient play to prevent the buckling or bending of the same under the heavy torsional strains imposed upon them.

In the car construction illustrated in Fig. 7, A⁴ represents the side thereof, B⁹ represents the side beams secured thereto and F¹¹ represents the purlins, upon which the carlines rest. The straight edge of the metal plates C⁸ extends slightly beyond the sides A⁴ of the car and engages within slots D⁸ of A⁴ securing plates D⁹ bolted through the side A⁴ and the side beam B⁹ by bolts D¹⁰. Thus the fastening of each element is provided for, securing plates D⁷ bolted through the side A⁴ and the side beam B⁷ by bolts D¹¹. Thus the fastening of each element is provided for, the outer ends of the carlines being covered by caps E¹⁰ fitting thereover and bolted or otherwise secured to the sides A⁴ of the car.

From the foregoing description it will be seen that I provide a construction in which the main elements are securely, though movably held in their relative positions in such manner as to allow of sufficient movement to prevent the buckling and bending of the metal plates under the strain put upon them by the pitching of the moving car and to allow the same to remain in their normal water-tight engagement.

Having thus described my invention, I claim:

In an inner car roof of the character described, the combination with a ridge pole having longitudinal undercut channels, and openings therethrough communicating with said channels, of a plurality of carlines having reduced ends fitting within said openings

and having longitudinal channels therein, a plurality of metallic roof plates having up-standing flanges on both sides and the upper end thereof, said end flange having an angular extension flange provided with an upwardly curled edge and adapted to lie within the said undercut channels of the ridge pole to form closures for the upper ends of the said carlines, and means to secure the outer ends

of said carlines and said plates, substantially as described.

In witness whereof I hereunto affix my signature in presence of two witnesses this 8th day of April, 1907.

JAMES MASKER.
